UNITED STATES PATENT OFFICE.

GEORGE L. BUFF, OF JAMAICA PLAIN, MASSACHUSETTS.

TRANSIT.

SPECIFICATION forming part of Letters Patent No. 719,429, dated February 3, 1903.

Application filed June 13, 1902. Serial No. 111,479. (No model.)

To all whom it may concern:

Be it known that I, GEORGE L. BUFF, a citizen of the United States, residing at Jamaica Plain, in the county of Suffolk and State of Massachusetts, have invented an Improvement in Transits, of which the following description, in connection with the accompanying drawings, is a specification, like letters on the drawings representing like parts.

10 My invention consists in improvements in measuring instruments, and particularly in engineers' transits.

It is usual in transits, where precision and accuracy are required, to provide two verniers one hundred and eighty degrees apart and two spirit-levels inclined toward each other at an angle of ninety degrees. The four standard-legs which customarily support the main telescope above the vernier-plate 15 divide the plate into four available spaces for locating the verniers and spirit-levels. It is therefore necessary that one vernier and one spirit-level occupy a portion of the vernier-plate falling between the same pair of 20 supporting-standards. This arrangement tends to cause conflict between the vernier and level nearest each other in the existing types of instruments, where the available 25 space is limited, and it has heretofore been customary to avoid this difficulty either by 30 providing a shorter spirit-level and sacrificing the increased sensitiveness incident to a longer bubble or overhanging one end of the bubble-case at the edge of the plate. In the 35 latter instance the overhanging or projecting end of the bubble-case is ordinarily supported by a bracket attached to the plate. In this construction, however, not only the projecting end of the level-case is itself exposed to 40 all manner of blows, thrusts, and displacements, which seriously impair the adjustment and accuracy of a sensitive level, but the supporting-basket increases this liability by 45 transmitting directly to the level all shocks of a like nature which it may receive.

One object of my invention is to overcome this liability to injury on the part of the overhanging spirit-level, and thereby to prevent undue strains and serious departure from the 50 normal adjustment, to which practice has shown the present forms of instruments to be subject.

A further object of my invention is to protect the exterior end of the needle-lifter in the compass-case from lateral or other displacement and at the same time prevent the access of moisture to the interior of the compass-case. In the common types of instruments now in use the compass-lifter extends through an oval opening in the walls of the 55 case and, being fulcrumed at some point thereabout, is engaged at its extreme outer end by one edge of an adjusting-screw threaded on a central post. The exterior end of the lifter is exposed to lateral displacement 60 incidental to general usage, which experience has shown often throws it out of engagement with the adjusting-screw, while the oval opening exposes the interior of the compass-case and the needle-bearing to the injurious effect 65 of moisture entering therethrough.

By my invention I protect the needle-lifter from all displacement and the interior compass-case from the entrance of moisture.

My invention will be better understood by 75 the following description of one specific embodiment thereof, taken in connection with the accompanying drawings, while its scope will be particularly pointed out in the appended claims.

80 In the drawings, Figure 1 is a plan view of a typical form of transit vernier-plate, showing my improvements applied thereto. Fig. 2 is a central sectional elevation taken on the diametrical line 2 2 in Fig. 1, and Fig. 3 is a detail view in elevation of one of the bubble-cases and its protector.

85 For the sake of simplicity I have shown an ordinary form of vernier-plate A, unobscured by other details of the instrument, the latter forming no part of my invention. The vernier-plate A has spirit-levels B and B', enclosed in the usual metallic bubble-cases, placed at an angle of ninety degrees with each other, and verniers C C' diametrically opposite each other. Holes a, a', a², and a³ are provided to locate the four supporting-standards for the main telescope. Level B and vernier C are placed between standards corresponding to holes a and a', which in this 90 case are the rear standards and are placed to permit the observer to read the same without substantial change in position.

95 The level B' is mounted, as is usual, upon

the plate by adjustable screws $b'c'$. Level B is similarly mounted on screws b and c , screw b , however, preferably passing loosely through the base of the protecting-bracket D to be 5 out of direct contact therewith and entering the plate A near its periphery. The bracket D, which I have provided to protect the level, has its base rigidly secured to the plate and is provided with protecting lugs or arms $d'd'$, so located as to form protecting-walls and shield said level from all lateral blows. Different forms of protecting-walls may be employed; but I have found the one shown well adapted to receive a blow or shock without 10 transmitting vibrations from the same to the base or the vernier-plate and without affecting the adjustment of the level. It is also possible by giving the base of the bracket great rigidity and making the protecting-walls relatively yieldable, such as is the case 15 with the bracket shown, to prevent to a degree the communication of shocks from the protecting-walls to the bubble-case when the latter is supported directly upon the bracket, 20 and such construction comes within the scope 25 of my invention, although the construction illustrated is my preferred form. The vernier-plate also has a compass-case E, provided with side walls c and the usual glass 30 face. A needle-lifter f passes through the walls of the case, being fulcrumed therein, and is adapted to raise the needle from its bearing on the pivot g on the depression of the exterior end of said lifter. A cap h , fastened to the vernier-plate, covers the exterior 35 end of the lifter and is fitted against the side walls of the compass-case with a substantially waterproof joint, preventing the access of moisture to the interior thereof. An adjusting-screw i is tapped into the cap and with 40 its tapered tip impinges centrally upon the end of the lifting-lever. The lifter being protected from lateral displacement and, moreover, being limited in its lateral movement 45 within the cap is always maintained in engagement with the adjusting-screw.

It is to be understood that the specific details shown are submitted for illustrative purposes only and that my invention is not limited thereto, but is capable of numerous embodiments.

I claim—

1. In a transit, a vernier-plate having a spirit-level with an end overhanging the edge of said plate but receiving its support directly therefrom, and a guard for protecting the overhanging end.
2. In a transit, a vernier-plate having a

spirit-level overhanging the edge of said plate and a guard unattached to said spirit-level for protecting said overhanging end. 6

3. In a transit, a vernier-plate having a spirit-level with an end overhanging the edge of said plate but receiving its support directly therefrom, a bracket attached to said plate provided with vertical protecting-walls to protect said spirit-level from lateral thrusts. 6

4. In a transit, a vernier-plate, a spirit-level therefor, a guard attached to said plate but out of direct contact with said level and having vertical protecting-walls to protect 70 said spirit-level from lateral thrusts. 70

5. In a transit a compass-case, a needle-lifter extending through the walls thereof, an external cap covering the exterior end of said needle-lifter and forming a substantially waterproof inclosure therefor and an adjusting-screw threaded into said cap and impinging upon the end of said lifter. 75

6. In a compass-case a needle-lifter extending through an opening in the walls thereof, a cap covering the end of said lifter and said opening and forming a substantially waterproof inclosure and an adjusting member 80 passing through the walls of said inclosure, 85 engaging with the end of said lifter.

7. In a compass-case a needle-lifter extending through the walls thereof, an adjusting member impinging centrally upon the end of said lifter and means for protecting that portion of the lifter exterior to the compass-case 90 from displacement due to lateral thrusts.

8. In a transit, a vernier-plate having a rigidly-supported spirit-level with an end overhanging the edge of said plate, and a guard 95 attached to said plate to protect said spirit-level from lateral thrusts.

9. In a compass-case a wholly-inclosed needle-lifter with means engaging the same located at the side of the compass-case and projecting outside of the side walls thereof adapted for external manipulation for raising and lowering the needle. 100

10. In a compass-case, a wholly-inclosed needle-lifting lever extending through the 105 walls of the case with means engaging the said lever and adapted for external manipulation for raising and lowering the needle.

In testimony whereof I have signed my name to this specification in the presence of 110 two subscribing witnesses.

GEORGE L. BUFF.
